ATTORNEY

UNITED STATES PATENT OFFICE.

AUGUST F. KAUFMAN, OF WHEELING, WEST VIRGINIA.

DESIGN FOR A STATUETTE OR TABLE ORNAMENT.

52,277.

Specification for Design.

Patented Aug. 20, 1918.

Application filed May 6, 1918. Serial No. 232,951. Term of patent 7 years.

To all whom it may concern:

Be it known that I, AUGUST FREDERIC KAUFMAN, a citizen of the United States of America, and resident of Wheeling, county of Ohio, and State of West Virginia, have invented an original and ornamental Design for a Statuette or Table Ornament, of which the following is a specification, reference being had to the accompanying drawings, in which—

Figures 1 and 2 are, respectively, front and rear perspective views of the statuette or table ornament which constitute my invention.

I claim:

The ornamental design for a statuette or table ornament, as shown.

AUGUST F. KAUFMAN.

Witnesses:

E. S. BIDDLE,
H. E. DUNLAP.
